PASTRY SHEET OR THE LIKE

Elsie M. Mortland, Kissimmee, Fla., assignor to Rexall Drug and Chemical Company, Los Angeles, Calif., a corporation of Delaware

Filed Feb. 17, 1966, Ser. No. 1,087

Term of patent 14 years

(Cl. D44—1)

FIG. 1

FIG. 2

FIG. 1 is a top plan view of a pastry sheet or the like showing my new design; and

FIG. 2 is a front elevational view.

The dominant features of my design reside in those portions shown in full lines.

The border decoration shown in the upper right-hand quadrant of FIGURE 1 of the drawing is continuous about the entire border and has been omitted in the remaining quadrants for ease in illustration.

I claim:

The ornamental design for a pastry sheet or the like, as shown and described.
